UNITED STATES PATENT OFFICE.

JOHN S. RUNYAN, OF COLUMBUS, OHIO.

CATCH-BASIN AND TRAP FOR SEWERS.

SPECIFICATION forming part of Letters Patent No. 391,339, dated October 16, 1888.

Application filed June 6, 1888. Serial No. 276,422. (No model.)

To all whom it may concern:

Be it known that I, JOHN S. RUNYAN, a citizen of the United States of America, residing at Columbus, in the county of Franklin and State of Ohio, have invented certain new and useful Improvements in Catch-Basins and Traps for Sewers, of which the following is a specification, reference being had thereto to the accompanying drawings.

10 My invention relates to improvements in the construction of sewers and the approaches to the same from the gutters of the streets.

15 The object of my invention is to provide a sewer-trap and cover which will admit the water and heavy débris from the street to enter the sewer and at the same time prevent the sewer-gas from escaping into the street.

20 My invention therefore consists of a sewer top or covering having a spout which will admit the water from the gutters, said spout projecting some distance into the vertical portion of the sewer-basin, the inner end of said spout being provided with a door whereby the stench and gases are prevented from coming 25 out into the streets.

25 Referring to the drawings, Figure 1 is a vertical sectional view of my improved sewer-top basin and sewer. Fig. 2 is a top view, partly in section, of the sewer-basin top and trap. 30 Fig. 3 is a sectional view of a portion of the top with the spout and valve or door.

35 A indicates the basin, which receives the water from the gutters of the street, and is made of masonry or other preferred form of construction. The basin or reservoir A communicates with the sewer B by means of the pipe C, said pipe entering the basin some distance above the bottom, so as to leave a place into which the dirt and other débris from the 40 streets will settle and collect, and from which it can be taken through the man-hole in the top of the basin.

D is the top or cover of the basin, which is

made of cast-iron or other suitable material, and provided with a man hole, E, through 45 which access is had to the basin. The top D is provided with an annular flange, a, to adapt it to rest firmly on the top of the masonry of the basin, and with shoulders or offsets b, against which the curbstones F abut. One 50 side of the top or cover D is provided with a pocket, G, having an opening, H, which is closed by the swinging door I, said door being hung on the hooks K. The hooks K are of such a form as will allow the door to rise 55 and swing inward in case large bodies should be carried into the pocket G and allow the same to pass into the basin. The pocket G has an inclined bottom, L, which projects some little distance in from the side of the basin, 60 and the door I fits snugly down against the edge of the same. This construction prevents the sewer-gas and offensive odors from coming out into the street, as the door or valve is closed at all times, except when the pressure 65 of water becomes too great in the pocket, when the door will yield and allow the water to pass into the basin. This is an important feature 70 of my invention, as the gases and noxious odors are prevented from passing out to foul 75 the atmosphere in the vicinity of the mouth of the basin.

What I claim, and desire to secure by Letters Patent, is—

In a cover for sewer-basins, the combination 75 of the spout L, with the door or valve I, and hooks K, engaging slots in said door, whereby the door is permitted to rise and allow large bodies to pass into the sewer.

In testimony whereof I affix my signature in 80 presence of two witnesses.

JOHN S. RUNYAN.
